UNITED STATES PATENT OFFICE.

FRANK L. WHEELER, OF SPENCER, INDIANA.

DEVICE FOR SECURING EXTRA LEAVES IN BOOKS.

1,333,521.

Specification of Letters Patent.

Patented Mar. 9, 1920.

Application filed February 27, 1919. Serial No. 279,500.

To all whom it may concern:

Be it known that I, FRANK L. WHEELER, a citizen of the United States, residing at Spencer, in the county of Owen and State of Indiana, have invented certain new and useful Improvements in Devices for Securing Extra Leaves in Books, of which the following is a specification.

This invention relates to a device for securing extra leaves in books which are already bound in such manner that the extra leaves may be removable or interchangeable at pleasure.

More specifically the invention comprehends the provision of a device for securing loose or extra leaves, such as are ordinarily used by ministers or preachers to contain notes on their sermons, in a Bible or bound book. The invention includes a pair of buttons or clasps which are detachably connected to the ends of the back of the book cover at the center thereof, to which buttons a string or strand of suitable material is connected, which string or strand is adapted to engage the loose or extra leaves or note sheets and bind their intermediate portions to draw the fold or intermediate portion of the note sheet tightly between the leaves of the book, thereby permitting the note sheet or auxiliary leaves to be turned as leaves of the book and permitting the reading of notes from both sides of the auxiliary or note leaf as well as reading the printed matter from the pages of the book which are adjacent to the note sheet.

Other objects of the invention appear in the following detailed description taken in connection with the accompanying drawing, forming a part of this specification, and in which drawing:

Figure 1 is a perspective view of a book showing the improved loose sheet holder attached thereto.

Fig. 2 is a longitudinal section through a book showing the loose leaf holder applied.

Fig. 3 is a section through one of the buttons of the loose leaf holder illustrating its manner of attachment to the back of the book cover.

Referring more particularly to the drawings, A indicates an ordinary book, the cover B of which overlaps the edges of the leaves of the book.

The device for securing the extra leaves in the book comprises a pair of buttons 1

and 2 and a cord 3 which is connected to these buttons.

Each of the buttons 1 and 2 comprise a pair of members 4 and 5 which may be made of any suitable material and have their outer surfaces rounded and colored in any suitable manner to conform with the color of the back C of the cover B of the book. The section 4 of the button is provided with a centrally disposed threaded recess 6 which receives therein the threaded portion of the shank 7 of an inserting member, the head 8 of which is adapted to be forced into a recess 9 formed centrally within the inner surface of the section 5 of the button. The shank 7 extends through an opening 10 formed in the back C of the cover B of the book and thus connects the section 4 of the button or snap to the back C, preventing accidental disconnection between the cover and the button, owing to the fact that the head 8 is of greater diameter than the shank 7 as clearly shown in Fig. 3 of the drawing. This head 8 is constructed in the same manner as the head of snap fasteners now commonly in use and snapped into the recess 9 to connect the section 5 thereto.

The section 5 of the button is provided with an opening 11 extending therethrough which opens into an enlarged recess 12 in the inner face of the section 5. The recess 12 receives one knotted end of the cord 3. This cord 3 may be made of a silken cord, elastic or any desired material, without departing from the spirit of this invention. The length of the cord may be cut to fit any desired book, and its ends being knotted in the recesses of the section 5 of the buttons 1 and 2, it may be stretched through the book A to bind the loose or auxiliary leaves indicated at 14 in the book A, in such manner as to permit the leaves to be turned as leaves of the book.

The device, while particularly adaptable for holding minister's or preacher's sermon notes in the Bible may be employed for detachably fixing loose or auxiliary leaves in any type of book.

In fixing the loose leaf 14 in place, it is folded or creased, intermediate its ends, so that the fold or crease therein will fit in the crease of the book A when opened and after the leaf 14 has been placed at the desired position within the book A, the cord C is passed thereover in the crease or fold

therein. Prior to the passage of the cord over the auxiliary leaf 14 one of the sections 5 of the buttons 1 or 2 has previously been attached to the head 8 of the said button 5 and therefore the cord is connected to the book cover and upon passage of the cord over the auxiliary leaves 14, the section 5 of the other button is connected to the section 4 thereof through the medium of the head 8, 10 securely binding the loose or auxiliary leaves 14 in place, in such manner as to permit the reading of notes upon each side of each page of the loose leaves and also the reading of the printed matter from the facing sides of 15 the adjacent pages of the book.

Changes in details may be made without departing from the spirit of this invention, but;

I claim:

20 1. A device for securing auxiliary leaves

in books comprising a pair of buttons each including a section adapted for attachment to a book back, a detachable section for connection with said first named section, and a cord detachably connected to said detachable section and adapted to extend across a book. 25

2. In a device for securing auxiliary leaves in books, the combination with a book cover having an opening in each end thereof, of a 30 pair of buttons each including a book carried section, a shank extending through the opening in said book cover and connected to said book carried section for attaching the book carried section to the book cover, a 35 head upon said shank, and a detachable button section adapted for connection with said head, and a cord connected to said detachable button sections.

FRANK L. WHEELER.
